DESIGN FOR A PENHOLDER

Benjamin W. Hanle, Elizabeth, N. J.

Application November 30, 1944, Serial No. 116,625

Term of patent 14 years

(Cl. D74—17)

To all whom it may concern:

Be it known that I, Benjamin W. Hanle, a citizen of the United States and residing at Elizabeth, in the county of Union and State of New Jersey, have invented a new, original, and ornamental Design for a Penholder, of which the following is a specification, reference being had to the accompanying drawing, forming part thereof and in which

Fig. 1 is a front elevation of a penholder showing my new design,

Fig. 2 is a side elevation thereof,
Fig. 3 is a top plan view thereof, and
Fig. 4 is a bottom plan view thereof.

The essential features of my design reside in the parts shown in full lines.

I claim:

The ornamental design for a penholder, substantially as shown and described.

BENJAMIN W. HANLE.
